Werner W. Stunkel, Skokie, Ill., assignor to The Motloid
Company, Inc., Chicago, Ill., a corporation of Illinois

Filed Jan. 2, 1962, Ser. No. 68,149

Term of patent 14 years

(Cl. D24—1)

Fig. 1.

Fig. 2.

Fig. 3.

FIG. 1 is a perspective view of a combined slab and drier for dental materials showing my new design;

FIG. 2 is a top plan view of the drier with the mixing slab removed.

FIG. 3 is a bottom plan view of the drier.

The portion of the cord member shown in FIGURES 2 and 3 is broken away in part to indicate indeterminate length.

The conventional channels shown on the bottom of the slab disclosed in FIG. 1, continue uniformly along the bottom surface thereof.

I claim:

The ornamental design for a combined slab and drier for dental materials as shown and described.
